UNITED STATES PATENT OFFICE.

AUGUST G. EICHHORN, OF ST. LOUIS, MISSOURI.

DETACHABLE HEEL FOR BOOTS AND SHOES.

Application filed August 1, 1922. Serial No. 578,909.

My invention relates to a detachable heel for shoes and boots and more particularly to fastening means for detachably securing a heel section, such as rubber or leather, to a stationary heel section which is secured to the heel portion of the shoe or boot, and it is a distinct and practical improvement to overcome certain practical objections to, and defects in, the present 10 method of securing, especially rubber heels, or tread sections to the heel of the boot or shoe.

A further object of my invention is the provision of novel means for locking the 15 detachable heel section to the stationary heel section of a shoe or boot.

A still further object of the invention is to provide a detachable heel section and fastening means therefor which will be 20 simple in construction, durable, easily and quickly attached and detached from the stationary heel section of a shoe or boot and prove highly efficient for the purpose intended.

A still further object of the invention is the provision of means which will permit of a rubber heel being securely applied to an aluminum heel, which has proven a failure heretofore.

With the above and other objects in view, the invention consists in the novel features of construction, arrangement and combination of parts hereinafter more fully described and finally pointed out in the claim 10 hereto appended.

Referring to the accompanying drawings forming a part of this specification, wherein like characters of reference denote similar parts throughout the several views:

Fig. 1 is a sectional view of a heel applied to a shoe embodying the features of my invention.

Fig. 2 is a sectional view thereof taken on line 2-2 of Fig. 1.

Fig. 3 is a part plan and part sectional elevation of the detachable heel section.

Fig. 4 is a perspective view of a shoe and the stationary heel section thereof, which is provided upon its lower face with socket members.

Fig. 5 is a perspective view of the detachable heel section.

Fig. 6 is a perspective view of the reinforcing lock plate adapted to be embedded in the detachable heel section. 55

Fig. 7 is a perspective view of the locking plate.

Fig. 8 is a detail showing the frictional locking means for the tongue.

Fig. 9 is a sectional view of the detachable heel. 60

Fig. 10 is a side elevation of a lady's aluminum heel with detachable heel applied thereto.

Fig. 11 is a perspective view of an aluminum heel for ladies' shoes with the detachable heel section removed. 65

Fig. 12 is a perspective view of the detachable heel section for aluminum heels for ladies' shoes. 70

Referring to the drawings, the reference character 1 indicates a heel portion of a shoe or boot and 2 represents the stationary heel section thereof, which may be made from leather, metal, or composition and of any desired shape or height, and which is provided in its front face with a suitable recess 3. Driven into the stationary heel section from the lower face thereof, or otherwise suitably fastened thereto are a plurality, preferably two suitably spaced U-shaped staples or similar fastening elements 4. These elements are so positioned as to provide an elongated loop or socket 5 for the reception of a locking plate, or tongue to be hereinafter described. 75

6 indicates a suitable detachable heel section made from any suitable material, such as rubber, leather, wood or composition and this heel section is provided with a longitudinally disposed flattened pocket, or socket 7, which communicates at its forward end with the front face of the heel section, as shown in Fig. 5. 80

The detachable heel section is provided with a metallic reinforcing plate 8 which is embedded or anchored in the rubber heel section 6 which also serves to form the upper face or roof of the socket 7. This plate is provided with anchor openings 9 when 85

- vulcanized in the detachable heel section 6 so that they may be filled with rubber for securely holding the plate from displacement. When applied to leather, wooden or composition heels, the plate is preferably nailed or otherwise suitably fastened in position. The plate 8 is further provided with a pair of transversely disposed slotted openings 10, as shown in Figs. 4 and 12.
- 10 The upper face of the detachable heel section 6 is provided with a pair of slotted openings 11 which register with the slotted openings in the plate 8 which latter openings communicate with the pocket or socket 7, as shown in Fig. 8 and these slotted openings are so positioned as to register with and permit the passage of the U-shaped fastening elements 4 of the stationary heel section 2 therethrough when the detachable heel section is applied to the stationary heel section 2 of the shoe or boot. The detachable heel section 6 is further provided with the U-shaped recesses 12 which receive the U-shaped fastening elements 4, as is evident from Figs. 2, 3 and 9. The recesses 12 lie below the plane of the lower face of the socket 7 and back from the plane of the side faces of the socket 7.
- 13 indicates a suitable locking plate or tongue which is insertable into the socket 7 of the detachable heel section 6 when this heel section is applied to the stationary heel section 2. The locking plate 13 also passes through the loops or sockets formed by the staple fastening means 4 and securely fastens the detachable heel section against displacement upon the stationary heel section 2, as will be apparent from the drawings.
- 40 The reinforcing plate 8 is further provided with a suitably shaped resilient protuberance 14 near one end for locking engagement in the opening 15 of the locking plate or tongue 13 when the latter is driven home in the socket 6 to prevent accidental removal of the locking plate or tongue 13 from its locked position for holding the detachable heel section 6 upon the stationary heel section 2, as is manifest. The reinforcing plate 8 is further provided at one end with a recess 16 which is adapted to register with the recess 3 in the front face of the stationary heel section 2 to permit the easy and quick insertion of a hook end 17 of a button hook or like element 18 to engage in the opening 19 of the locking plate or tongue 13 for removing or extracting the plate or tongue 13 from its socket 6 when in its locked position to permit the heel section 6 being quickly detached from the stationary heel section 2 of the boot or shoe without even having to remove the boot or shoe from the foot, if desired, for the replacing of a new detachable heel section 6 after

the same has become worn upon its tread surface.

From the modification shown in Figs. 10, 11 and 12, it is evident that a detachable rubber or other heel tread section 6 may be applied to aluminum heels for ladies' shoes, 70 designated 20, as conveniently as to any other make or type of heel thus providing a tread section for aluminum heels which will not be subject to falling off or being easily displaced which is the trouble now experienced with the tread lifts of aluminum heels for ladies' shoes. When the detachable heel section 13 is applied to aluminum heels for ladies' shoes, designated 20 in Fig. 11, the U-shaped fastening elements 80 are cast in the lower face of the heel, as shown in Fig. 11. The detachable tread section 13, as shown in Fig. 12, is made to conform to the size and shape of the lower face of the aluminum heel, as is manifest. 85

From the foregoing description, it is evident that I provide a detachable heel or tread section for any type of shoe or boot heel which is simple in construction, effectively locked in position, easily and quickly detached and which will in every respect, prove highly efficient for the purpose intended. 90

The many advantages of the invention herein described will readily suggest themselves to those skilled in the art to which it appertains. 95

I do not wish to be understood as having limited myself to the exact details of construction shown and described, but desire to have it understood that the invention I have shown in the drawings is merely illustrative, as it is manifest that various minor changes may be made in the exact construction and particular arrangement of parts without departing from the spirit of my invention, hence I reserve the right to make any such changes, or modifications, as may fairly fall within the scope of the appended claim when fairly construed. 100 105 110

What I claim is:—

In a detachable heel structure for boots and shoes, a stationary heel section, a pair of aligned elongated socket members fixed to and depending from the heel section in such a manner as to span the center line of the heel section, a detachable heel section having a pair of spaced transversely disposed sockets communicating with a single longitudinally disposed interior socket which is provided with an open end communicating with the breast of the detachable heel section, a marginally perforated metallic plate provided with a pair of spaced elongated openings registering with the transversely disposed sockets embedded in the detachable heel section and acting as the ceiling of the longitudinally disposed 115 120 125

interior socket, a recess formed in the breast of the stationary heel section, a recess formed in the breast of the detachable heel section and a metallic locking strap slidably receivable in the longitudinally disposed interior socket of the detachable heel section and engaging in the elongated sockets of the stationary heel section, said locking

strap being provided with an opening adjacent the breast recesses of the stationary and detachable heel sections for receiving an extracting element and means to prevent accidental removal of the locking strap.

In testimony whereof, I have hereunto signed my name to the specification.

AUGUST G. EICHHORN.
